UNITED STATES PATENT OFFICE.

WILLIAM F. KIESEL, JR., OF ALTOONA, PENNSYLVANIA.

DUMP CAR.

Application filed November 26, 1920. Serial No. 426,558.

To all whom it may concern:

Be it known that I, WILLIAM F. KIESEL, Jr., a citizen of the United States, and residing at Altoona, Blair County, State of Pennsylvania, have invented certain new and useful Improvements in Dump Cars, of which the following is a specification.

This invention relates to dumping vehicles and particularly to railroad dump cars of the side door type, which are especially adapted for conveying dirt, cinders or ballast, such as broken stone or gravel.

The principal objects of the invention are; to provide a dump car of this class which may be conveniently loaded by a workman standing on the roadbed alongside of the same; which may be easily dumped when it is desired to discharge the contents thereof by an operator stationed on the platform at either end of the car or by the joint action of two operators one stationed at each end of the car; which is so designed that the load carried may be dumped in its entirety to one side of the car or a part of the load on one side and a part on the other side of the car, which is tilttable in either direction; or a portion of the load at one point along the track and another portion or the remainder at another part; and which may be tilted to any desired inclination from the horizontal and held in such position as long as desired. Other objects and advantages of the invention will become apparent as it is disclosed in the following description when taken with the accompanying drawings, in which:

Fig. 1 illustrates partially in side elevation and partially in longitudinal section a railroad dump car embodying the features of the invention, the running gear being omitted for the sake of clearness;

Fig. 2 is a top view of the car, a portion of the body being broken away to show the supporting frame;

Fig. 3 is an end elevation of the car;

Fig. 4 is a transverse section showing the car in dumping position;

Fig. 5 is a longitudinal section through the windlass mechanism for tilting the body;

Fig. 6 is a partial transverse section through the car body partly broken away to show the intermediate latches securing the adjacent ends of two of the side doors;

Fig. 7 is a section on line 7—7 of Figure 6;

Fig. 8 is a similar section but showing the

end latches for securing the outer end of one of the end doors of the car;

Fig. 9 is an enlarged view of the ratchet mechanism contained in an operating lever; 60

Fig. 10 is a section on line 10—10 of Figure 9;

Fig. 11 is an enlarged view of a portion of the latch operating mechanism;

Fig. 12 is a section on line 12—12 of Figure 5;

Fig. 13 is a detail; and

Fig. 14 is a cross section through a cam member illustrated in Figures 9 and 10.

The frame of the car has the usual end bolsters 9 which are connected by a center sill 10 extending continuously from one end of the frame to the other, this center sill being preferably formed as illustrated, of parallel channel members placed in close proximity to each other and arranged back to back with a plate 10^a secured to and connecting their top flanges, as shown in Figure 4. The frame has no side sills. Upon the end platforms may be mounted the usual brake operating mechanisms, bumpers, etc. which will not be described in detail, forming no part of the present invention. Bearing blocks 11 are supported on the center sill, these blocks being positioned toward the ends of the sill and adjacent the end platforms. Each of these blocks comprises a strong casting or forging and is formed with upwardly extending flanges 12 which extend longitudinally of the car and have semicylindrical upper surfaces which comprise bearings upon which rest correspondingly formed seats 13 of an intermediate block 14. Each of these blocks 11 has an opening therethrough between the spaced flanges 12 which receives the downwardly projecting tongue 14' of intermediate block 14. The side faces of these tongues 14' are curved concentrically with the curved upper surfaces of the flanges 12 so that when the car body is tilted, as illustrated in Figure 4, the tongue 14' will not bind against either of the flanges 12 to interfere with the tilting action.

The tilting body, which is preferably fabricated entirely of steel, is rectangular in plan, with upwardly inclined floors at the ends thereof, as clearly illustrated in Figure 1, and rigidly secured beneath the upwardly sloping end portions are brackets 15, 110 the lower ends of these brackets being provided with elongated transverse seats which

fit over the rounded transverse elongated upper portions 14" of the intermediate blocks 14. The entire weight of the detachably body is transmitted to the bearing blocks 11 and thereby to the frame, through the brackets 13. When the car is in its horizontal position this weight is divided equally between the four flanges 12 but when the car is tilted its entire weight rests upon a single pair of aligned flanges inasmuch as the intermediate blocks tilt with the body. The central tongues 14' of the bearing blocks serve to prevent lateral displacement of the tilttable body relatively to the supporting frame when the body is in its extreme position, as illustrated in Figure 4 or, when due to vibrations caused by a rough roadbed, the body has a tendency to jump laterally relatively to the frame. The intermediate block is held in position by the weight of the car body and if the body is lifted by power means the blocks may be removed and inspected and replaced by blocks of different size, if necessary to adjust the relative heights of the ends of the dump body.

The central longitudinal floor supports 16 of the body are upwardly inclined at their ends, but the horizontal middle portions of these members are located to either side of the center sill 10 of the frame and not above the center sill, as in side dump cars hereto designed or suggested. The central portion of the car floor is rigidly supported by these beams while at the same time the floor is not elevated because of them, but occupies a position at an elevation about forty inches from the roadbed, in this particular embodiment of the invention, an elevation which may be readily reached by the shovels of workmen standing on the roadbed and engaged in loading the car. The center sill 10 and the floor supports 16 do not contact or interfere with each other in any manner in tilting the car, which may be rotated to any angle permitted by the windlass mechanism hereinafter to be described.

The body has four swinging doors 17 on each side, these doors being pivotally supported on longitudinal rods 18 and being secured when in their closed positions by suitable latches mounted on the intermediate bracket-partitions 19 and end brackets 20, rigidly secured to the car floor. The intermediate bracket-partitions 19 are six in number and each comprises essentially two spaced triangularly shaped parallel plates between which is located a latch containing chamber or housing 21. The intermediate brackets 19 are disposed in pairs arranged transversely of the car so that the car body is divided into a series of communicating compartments. The latch mechanism controlling the doors is so arranged that any one or any number of the doors may be

opened so that when the car is tilted the contents may be either partially or wholly discharged as desired, the triangular intermediate brackets serving to retain a considerable portion of the cargo in a "closed" compartment even when the door of the adjoining compartment is open and in spite of the fact that part of the contents of the compartment may escape through the opening between the brackets or bracket-partitions.

The end compartments are, of course, shaped differently from the intermediate compartments, the floor of the end compartments being inclined and these compartments are therefore not provided with doors, any material therein being necessarily discharged through the door of the adjacent compartment when the car is dumped. To prevent material being retained in these end compartments each is provided with two sloping plates 22, the lower edges of each plate being secured to the inclined car floor and the upper edges of which are secured to the top of the side wall of the compartment and to one of the triangular end brackets 20 respectively. Material can not be retained, therefore, behind these end brackets 20, but pours through the opening between them and out through the adjacent compartment when the door of the adjacent compartment is unlatched, and the car has been tilted.

The doors 17 are pivotally mounted on bars 18 which are in turn rotatably mounted in brackets 23 supported upon the side sills 24 of the car body, and the doors are secured in their closed positions by latches mounted on the triangular intermediate bracket-partitions and end brackets and which are adapted to engage the upper portion of each door at each end thereof to hold the door closed against the pressure of the material in the car. On each of the intermediate brackets 19 are supported latches for securing the adjacent ends of two doors, while on the end brackets 20 are latches for securing only the outer ends of the end doors.

In Figures 6 and 7 a set of intermediate latches is clearly illustrated. Each of the doors adjacent one of these latches is notched as at 25 and is provided with a reinforcing plate or catch 26. A horizontal axle or shaft 26a extends transversely through the latch housing 21 and pivoted on this shaft are three latches, a center latch 27 having laterally projecting lugs 28 each of which is adapted to engage a catch 26 of an adjacent door, and two side latches, each adapted to engage catch 26.

The center latch has forwardly extending fingers 29 having aligned apertures therein in which is mounted a short shaft or axle 30. This axle rotatably supports the upper end 130

- of a link 31, the lower end of which is pivotally connected to an arm 32 bolted to shaft 18 for rotation therewith. The side latches 33 are slotted and are adapted to be lifted 5 by hand to disengage catches 26 and to be moved rearwardly from the full line position to the dotted line position (Figure 6), where they will rest within the latch housing until again drawn forwardly and placed 10 in operative position. The center latch 27 will be raised by the connecting link 31 which is actuated by the arm 32, when the shaft 18 is rotated by means of an operating handle 34.
- 15 Each end latch housing 35 has a transverse axle or shaft 36 which rotatably supports a manually operable latch 37 and a second latch 38 adapted to be operated by a link 39 connected to shaft 18. In Figure 20 8 an end latch housing and the two latches therein contained are clearly illustrated, the end of a door being indicated at 17 and each of these latches engaging a catch 40 secured below the notch 25 of the door.
- 25 It will be seen, therefore, that each door of the car is held in closed position by two sets of latches, one set of which is raised when the lever 34 is manipulated to rotate shaft 18, and the latches of the other set 30 being lifted individually by hand. Inasmuch as no door can open when the car is tipped unless both sets of latches are disengaged, it is obvious that any single door or any particular doors, selected may be 35 opened for dumping while the other remain closed. If all of the manually operable latches along one side of the car are raised and placed in inoperative position, all of the doors will be completely unlatched 40 when the lever 34 on that side is manipulated. On the other hand, if the manually operable latches controlling any particular door are not raised, that door will remain closed when the power operated latches are 45 raised. In this manner the amount of material dumped at any particular point may be readily controlled.
- 50 Windlass mechanisms for tilting the body are mounted at the ends of the car. Each of the mechanisms includes a drum 41 rotatably mounted on an axle 42 which is supported in brackets 43 and 44 respectively secured to the frame of the car, and means for rotating the drum by hand. A large gear 45 is 55 rigidly secured to the drum 41 or is preferably made integral therewith, as shown in the drawings, and meshing with this gear is a pinion 46 fast on shaft 47 which shaft is rotatably mounted in the U-shaped upper 60 end of bracket 44.
- The outer end of shaft 47 is squared and power is applied to the squared end by means of a pawl and ratchet mechanism to rotate the drum. This mechanism comprises essentially an operating arm 48 having an en-
- larged end portion which is hollowed out to form a housing for the ratchet wheel 49, the reversible pawl 50, and the means for reversing the pawl. This housing has a removable cover plate 51 and this plate and the 70 opposite wall of the housing are provided with aligned apertures in which are journaled the hubs 52 of the ratchet wheel. The squared end of hub 47 extends through a correspondingly squared aperture in the 75 ratchet wheel and supports the same and hence also the operating arm. The reversible pawl 50 is pivotally supported and either of its ends may be brought into engagement with the teeth of the ratchet wheel for 80 the purpose of rotating the same and the shaft 47 and drum 41 in either direction. To this pawl is pivotally secured a leaf spring 53 which extends rearwardly between the knife edges or abutments 54, through a 85 slot in the transverse partition 55 and has its end in engagement with a cam 56. This cam is fixed on a short shaft 57 rotatably mounted in the walls of the housing and has a segmental recess 58 therein adapted to receive the end of the spring as it rotates and to shift the end of the spring from one side of the cam to the other, causing it to pivot about abutments 54 as fulcrum points and to reverse the pawl 50.
- 90 To one end of shaft 57 is secured an operating lever 59 by means of which the shaft and cam may be rotated through substantially 240°, the rotatory movement being, limited by stops 60 against which the lever 95 59 abuts. In Figure 9 the cam is shown in one of its extreme positions, the end of spring 53 being forced to one side thereby and this spring serving as a lever, forcing one end of the pawl 50 into engagement with the ratchet wheel. If it is desired to reverse the pawl, the cam is rotated in the direction of the arrow (Figure 9) to its other extreme position, the end of spring 53 entering the recess 58 in the pawl as the cam is 100 rotated and being forced from said recess as the cam approaches its opposite extreme position. By means of this pawl and ratchet mechanism, the shaft 47 and hence the drum 41 may be rotated in either direction as 105 desired.
- 110 A chain 61 has its ends secured to the upper corners of the tilting body, this chain passing over sheaves 62 mounted in the frame and passing twice around the drum 41, being secured thereto by bolts 63. By rotating the drum, therefore, the chain on one side thereof is paid out and on the other side is drawn in, thus tilting the car. As a preliminary step, however, one of the gravity actuated pawls 64 must be raised to allow the gear 45 to rotate. These gravity actuated pawls, when both are in engagement with the teeth of gear 45 will prevent rotation of the drum in either direction, and will 115 120 125 130

hold the car against accidental tilting or will hold it tilted to any angle found desirable for dumping purposes.

The car may be operated from either end or, if desired, the windlass mechanisms at both ends may be used simultaneously. When loaded the center of gravity of the body is a considerable distance above the fulcrum points thereby rendering it easy to tilt, while, when the body is empty, the center of gravity is very close to the fulcrum points so that it has great stability. The design and arrangement of the various parts of the dump car may be changed as found convenient in practice and the invention is, of course, not limited in scope to the exact embodiment described and illustrated.

Having thus described the invention what is claimed as new and desired to be secured by Letters Patent is:

1. In a dump car, in combination, a tilt-able body having a door, and two latches controlling said door one of said latches being adapted for direct manual manipulation, and the other latch being indirectly operable, for the purpose set forth.

2. In a dump car, in combination, a tilt-able body having a discharge aperture, a door pivotally secured to said body and normally closing said aperture, and two independently operable latches normally securing said door in closed position, one of said latches being adapted for direct manual manipulation, and the other of said latches being indirectly operable.

3. In a dump car, in combination, a tilt-able body having a discharge aperture, a door pivotally secured to said body and normally closing said aperture, and a plurality of latches normally holding said door in closed position, one of said latches being manually operable, and mechanism for operating another of said latches.

4. In a dump car, in combination, a tilt-able body, a plurality of doors hinged to one side of said body, two latches for securing each of said doors in closed position, said latches being independently operable, and mechanism for operating one latch at each door.

5. In a dump car, in combination, a tilt-able body, a plurality of doors hinged to one side of said body, two latches for securing each of said doors in closed position, said latches being independently operable, and mechanism for simultaneously operating a series of said latches including one latch at each door.

6. In a dump car, in combination, a tilt-able body, a plurality of doors hinged to one side of said body, two latches for securing each of said doors in closed position, said latches being independently operable, and mechanism for simultaneously operating a series of said latches including one

latch at each door, said mechanism including a rotatable shaft and means connecting said shaft and each latch in the series.

7. In a dump car, in combination, a tilt-able body, a plurality of doors pivotally secured to said body, an individually operable latch normally maintaining each of said doors in closed position, a second latch for each of said doors and normally maintaining the same in closed position and means for simultaneously operating all of said second latches, said means including a rotatable shaft extending longitudinally of said body, and a link operatively connecting each of said second latches with said rotatable shaft.

8. In a dump car, in combination, a tilt-able body, a rotatable shaft extending longitudinally of said body, a plurality of doors pivotally supported on said shaft, latches normally holding said doors in closed position and connections between said latches and said rotatable shaft whereby the latches will be operated when the shaft is rotated.

9. In a dump car, in combination, a tilt-able body, a shaft rotatably supported on said body, a door pivotally supported on said shaft, a latch for normally holding said door in closed position, and a link connecting said latch and said rotatable shaft whereby the latch will be operated when the shaft is rotated.

10. In a dump car, in combination, a tilt-able body, two doors pivotally supported on said body, and a common latch positioned to engage the adjacent edges of the doors to hold them both in closed position.

11. In a dump car, in combination, a tilt-able body, two doors pivotally supported on said body, and a common latch extending between the adjacent edges of the doors and adapted to engage the outer faces of the doors to hold them in closed position.

12. In a dump car, in combination, a tilt-able body, two doors pivotally supported on said body, and a common latch pivotally supported in rear of the doors and adapted to engage their outer faces at their adjacent edges, to releasably hold the two doors in closed position.

13. In a dump car, in combination, a tilt-able body, two doors pivotally supported on said body, and a common latch pivotally supported in rear of the doors and extending outwardly between the adjacent edges of the doors and having laterally extending portions adapted to engage the outer surfaces of the doors.

14. In a dump car, in combination, a tilt-able body, two doors pivotally supported on said body, and a common latch having a main portion pivotally supported in rear of the doors to rotate about a horizontal axis and extending outwardly between the adjacent edges of the doors, the projecting end of said main portion having lateral exten-

sions to engage the front faces of the doors.

15. In a dump car, in combination, a tiltable body, two doors pivotally supported on said body, a common latch for engaging the adjacent portions of the doors to hold them both in closed position, and means connected to said latch for operating the same from a remote position.

16. In a dump car, in combination, a tiltable body, two doors pivotally supported on said body, a common latch for said doors, said latch being pivotally supported in rear of the doors and extending outwardly between the adjacent edges of the doors to engage their outer surfaces, and means connected to the outer end of the latch to operate the same from a remote position.

17. In a dump car, in combination, a tiltable body having a door, and two latches for controlling said door, one of said latches being adapted for independent manual manipulation, and the other latch being indirectly operable, both of said latches being rotatably mounted on a single pivot.

25. 18. In a dump car, in combination, a body portion, bracket members dividing said body portion into compartments, a door for each of said compartments pivotally supported on the body, and latches on said bracket members for normally holding said doors in closed position.

19. In a dump car, in combination, a body portion, opposed transversely extending brackets dividing said body portion into communicating compartments, and a door at each side of each compartment, for the purpose set forth.

20. In a dump car, in combination, a supporting frame having a single centrally located sill, a tiltable body pivotally supported on said sill, said body having longitudinal floor supporting beams equidistantly spaced from said sill and substantially in the same horizontal plane.

45. 21. In a dump car, in combination, a body portion, transversely extending substan-

tially triangular brackets dividing said body portion into communicating compartments, and a door extending longitudinally between each two adjacent brackets.

50

22. In a dump car, in combination, a supporting frame, a body, and a connection between the frame and body comprising spaced bearing members on the frame, seats for said members on the body, said bearing members supporting the weight of the body at all times, and a tongue on the body and extending downwardly between the bearing members to lock the body against lateral movement relatively to the frame at all times.

55

23. In a dump car, in combination, a frame, a body portion pivotally mounted on said frame and means for tilting said body portion in either direction, said means including a ratchet mechanism having a reversible pawl.

60

24. In a dump car, in combination, a frame, a body pivotally mounted on said frame, and means for tilting said body in either direction, said means including a ratchet, a reversible pawl and means for reversing said pawl.

65

25. In a dump car, in combination, a frame, a body pivotally mounted on said frame, and means for tilting said body in either direction, said means including a ratchet, a reversible pawl and means for reversing said pawl, said means comprising a rotatable cam and a member connecting said cam and pawl.

70

26. In a dump car, in combination, a frame, a body pivotally mounted on said frame, and means for tilting said body in either direction, said means including a ratchet, a reversible pawl and means for reversing said pawl, said means comprising a leaf spring secured to said pawl, and a rotatable cam engaging the end of said leaf spring, for the purpose set forth.

75

In testimony whereof I affix my signature.
WILLIAM F. KIESEL, JR.
